UNITED STATES PATENT OFFICE.

LAURENCE E. TOPHAM, OF WENHAM, MASSACHUSETTS, ASSIGNEE TO UNITED SHOE MACHINERY CORPORATION, OF PATERSON, NEW JERSEY, A CORPORATION OF NEW JERSEY.

METHOD OF MAKING SHOES.

Application filed December 18, 1926. Serial No. 155,625.

The present invention relates to certain operations which are performed progressively along the bottom margin of a shoe while supported upon a last and more particularly to the operations which form and finish the sole edge.

The object of the invention is to facilitate the operations which form and finish the sole edge and enable these operations to be performed in an accurate and reliable manner to produce satisfactory and uniform results without any special skill or care on the part of an operator.

With this object in view the invention contemplates presenting a lasted shoe successively to an edge trimming tool and to an edge setting tool and during each operation imparting predetermined relative tipping positioning movements to the shoe and tool timed and controlled to present the working face of each tool at the same angle to the sole surface at corresponding points throughout the operation of the tools. The sole edge is thus formed at the first operation and since the relative tipping positioning movements are predetermined as to time, direction and extent the edge surface will lie at the desired predetermined angle to the sole surface at all parts of the shoe.

During the second operation the working face of the setting tool is always maintained at an angle to the sole surface coinciding with the angle of the edge surface so that the entire edge surface is acted upon in a uniform manner and the finished edge is of predetermined shape and appearance. Preferably during each operation the shoe is guided and its position transversely of the direction of feed is determined by the engagement of a guiding device with an outline on the shoe so that the sole is trimmed to an exact predetermined outline and the edge setting tool is caused to act uniformly along all parts of this outline.

The present invention contributes to the production of shoes uniform as to shape and appearance and since the steps are such as are readily carried out by the use of automatic machinery the invention makes possible a reduction in the cost of production and the elimination of errors incident to the use of manual labor.

The invention will be readily understood from the following description taken in connection with the accompanying drawings in

which are illustrated an automatic edge trimming machine and an automatic edge setting machine which may be utilized in carrying out the several steps of the present invention.

In the drawings Fig. 1 is a view in front elevation of the edge trimming machine. Fig. 2 is a view in side elevation of the machine looking from the right. Fig. 3 is a plan view of a portion of the machine. Fig. 4 is a view in side elevation of the trimming head of the machine. Fig. 5 is a view similar to Fig. 4 illustrating certain of the parts in different positions. Fig. 6 is a detail plan view illustrating the jack supporting and actuating mechanism and certain associated parts. Fig. 7 is a detail plan view of a portion of the mechanism shown in Fig. 6. Fig. 8 is a view in side elevation partly in section of a portion of the machine illustrating particularly the jack supporting and actuating mechanisms. Fig. 9 is a view in side elevation of the head of the edge setting machine looking from the right. Fig. 10 is a view similar to Fig. 9 with certain of the parts in different positions; and Fig. 11 is a detail view in vertical section of a portion of the head of the edge setting machine.

The edge trimming and edge setting machines illustrated in the drawings are automatic in their action and are designed to guide a shoe so as to cause the point of operation to follow an outline determined by an outline of the shoe. As the point of operation is transferred around the shoe tipping positioning movements are imparted to the shoe to cause a sole edge to be formed during the edge trimming operation the edge surface of which is disposed at a predetermined angle to the sole surface at all points on the shoe and to cause this surface, during the edge setting operation, to be presented always in a predetermined plane at the point of operation. Each machine comprises tools for operating upon a shoe, which tools, as regards the transfer of the point of operation about the work, are fixed in position. Each machine also comprises a shoe supporting jack which is mounted in the machine so as to be capable of being moved to transfer the point of operation around the shoe and to be tipped and turned to present the shoe in the desired manner to the tools.

As the point of operation is transferred

around the shoe, tipping and turning movements predetermined as to time and extent are imparted to the shoe through connections to the jack from a pattern cam shaft. The edge trimming machine is provided with two edge trimming cutters one adapted to operate upon the forepart of the sole and one adapted to operate upon the shank portion of the sole. The edge setting machine 10 is also provided with two tools one of which is adapted to operate upon the forepart of the sole and the other upon the shank portion of the sole. The movement of the jack to transfer the point of operation around the 15 shoe as well as the tipping and turning movements are imparted to the jack through connections from the pattern cam shaft.

In order to permit the tools to be changed by the operator to bring either the forepart 20 or the shank tool into operation means are provided in each machine for automatically stopping the pattern cam shaft when the point at the junction of the shank and forepart on each side of the shoe is reached. Also 25 means are provided for automatically stopping the pattern cam shaft when the operation on the shoe is completed. To return the jack to its initial or starting position the operator moves the shoe away from the operating tools and then throws into operation mechanism which completes the rotation of the pattern cam shaft.

The edge trimming machine has the same general construction and mode of operation 35 as the machine disclosed in applicant's Patent No. 1,616,715, granted Feb. 8, 1927. The head of the edge setting machine is similar to that of the machine disclosed in applicant's Patent No. 1,616,717 granted Feb. 8, 40 1927. The base of the edge setting machine, however, is similar to that of the edge trimming machine and for this reason has not been separately illustrated.

The edge trimming mechanism of the edge 45 trimming machine, (see Figs. 4 and 5) comprises a rotary cutter shaft 12 mounted in an adjustable carriage 14. The cutter shaft is driven through intermeshing spiral gears 16 and 18 from a horizontal shaft 20 which constitutes the main shaft of the edge trimming head. The main shaft 20 has bearings formed in the carriage 14 and is driven from 50 an electric motor indicated at 22 secured to the carriage.

Upon the lower end of the cutter shaft 12 are mounted a cutter 24 for operating about the forepart of the shoe sole and a cutter 26 for operating along the shank. Upon the lower end of the shaft is also mounted a 55 yielding sleeve 28 arranged to slide longitudinally of the shaft and provided with projections extending between the blades of the cutter 24 for engagement with the sole of the shoe.

To enable a shoe to be located and held

in operating position with relation to the trimming cutters, the machine is provided with a work table 30 arranged to engage in the crease between the upper and projecting margin of the shoe sole. The work table is 70 secured to an arm 32 on the frame and is arranged to extend in front of the cutter which is in operating position.

To enable the cutters 24 and 26 to be moved alternatively into position to trim the 75 sole edge mechanism is provided for adjusting the cutter shaft to shift the position of the lower end thereof both vertically and horizontally. In the construction shown, the carriage 14 is eccentrically mounted in a bearing in a supporting ring 34 which is adjustably mounted in a bearing formed by arms 36 on the frame of the machine. To prevent the carriage 14 from turning with the ring 34 and to give certain movements 80 to the cutter shaft during the adjustment of the ring, the carriage is connected with the frame by means of a link 38. An operating handle 40 is secured to the supporting ring 34.

When the edge trimming operation is started along the shank of the shoe, the ring 34 is located in the position shown in Fig. 5 and the cutter 26 is in operating position. When the forepart of the shoe sole is reached the ring 34 is shifted into the position shown in Fig. 4. During this movement of the ring a movement is imparted to the cutter shaft carriage which places the cutter 24 in operating position. When the shank of the shoe is reached in trimming the last side of the shoe, the ring 34 is turned back to the position shown in Fig. 5 thereby bringing the cutter 26 back into operating position. The arms 36 on the frame may be relatively 95 adjusted so that they will exert sufficient friction on the ring 34 to hold the same in adjusted position by means of an adjusting screw 42.

The jack for supporting a lasted shoe 100 comprises a spindle 44, a toe supporting arm 46 rigid with the spindle and a heel supporting arm 48 pivoted to the spindle. The spindle is supported at its lower end by devices which comprise a wheel 50 rotatably mounted on a stud 52 and connected with the spindle by a gimbal joint. The stud 52 is supported at the forward end of a yoke 54 pivoted to swing in a vertical plane on a second yoke 56. The yoke 56 in turn is pivoted to swing in a horizontal plane on a link frame 58 carried by and connecting the swinging arms 60 and 62. The forward end of the yoke 54 is held up yieldingly by means 115 of a coiled spring 64. The force exerted by this spring, however, is less than the force exerted by gravity on the jack so that the margin of the shoe sole exerts a certain amount of downward pressure on the work table 30 during the operation on the shoe 120 125 130

and the shoe is partially supported by the table.

The shoe is held at all times at the point of operation by the engagement of the table 30 in the crease between the upper of the shoe and the projecting margin of the sole. Relatively slight vertical movements are imparted to the jack and the shoe by the cooperative action of the spring 64 and the table 30 which serves as a guide for the shoe.

The required tipping movements are imparted to the shoe by the devices acting on the jack spindle to move the lower end of the spindle forwardly, rearwardly, and laterally of the machine in horizontal directions and lateral turning movements are imparted to the shoe by devices acting on the jack spindle to rotate the spindle. Because of the fact that the shoe is held at all times at the point of operation by the table 30, the tipping and turning movements imparted to the shoe are caused to take place about said table as a fulcrum.

The lower end of the spindle is moved forwardly and rearwardly and laterally in opposite directions to tip the jack and the spindle is rotated to turn the jack through suitable connections from a series of cams 30 mounted on a shaft 66 which for convenience may be termed the pattern cam shaft.

Forward and rearward movements are imparted to the lower end of the jack spindle by means of a cam roll 68 mounted on a lever 35 pivotally connected with the frame and to the arm 60 the roll being arranged to engage a cam groove in a cam disc 72 mounted on the pattern cam shaft 66. The connections for moving the lower end of the spindle laterally from a cam on the cam shaft 66 comprises a bell crank lever 74, a link 76 connecting a depending portion of the yoke 56 with the bell crank lever, a lever 78 connected with the bell crank lever, and a cam roll 80 arranged to engage a cam groove formed in the underside of the cam disc 72.

The mechanism for rotating the jack spindle comprises a cable 82 passing about the wheel 50 and about a series of guide rolls 84, 86, 88 and 90, a pivoted segment 92 to which one end of the cable is secured and a weight 94 secured to the other end of the cable. The swinging movements of the segment 92 are produced and controlled by a cam lever 96 one arm of which is connected with the segment 92 by intermeshing gear segments and the other arm of which carries a cam roll 98 arranged to engage a peripheral cam on a cam disc 100 mounted on the cam shaft 66.

The jack spindle is acted upon by mechanism tending to swing the jack about the connection between the lower end of the spindle and the wheel 50 toward the rear of the machine. This mechanism comprises a rod

102 connected at its forward end with the jack spindle and acted upon at its rear end by devices tending yieldingly to move the rod rearwardly.

The edge trimming machine illustrated in the drawings is provided with a movable gage indicated at 104 for guiding the shoe to determine the distance at which the shoe is trimmed from the upper. The gage is pivotally mounted at 106 on an arm on the frame of the machine and it is constructed to extend upwardly from its pivotal point to a point just below the work table 30 so that its upper end will engage the upper of the shoe. The contour of the shoe which is engaged by the gage 104 is somewhat irregular in outline and to compensate for the irregularities in this outline as well as to compensate for certain of the positioning movements which are imparted to the shoe and to cause a wider projecting margin to be left on the sole about the forepart of the shoe than along the shank, mechanism is provided for actuating the gage from the pattern cam shaft 66.

The mechanism for actuating the gage 104 comprises a rock shaft 108 mounted in bearings in the frame and an eccentric disc 110 secured to the shaft and arranged to engage a downwardly extending arm on the gage. The gage is acted upon by spring 112 which normally maintains the lower end thereof in contact with the eccentric disc. The shaft 108 is rotated to advance and cause the retraction of the gage by means of a gear segment 114 secured to the rock shaft and an intermeshing gear segment 116 formed on a swinging arm 118 secured to a rock shaft 120. On the rock shaft 120 is secured another arm 122 which carries a roll 124 engaging a contact face formed on the outer end of an arm 126 secured to a vertical shaft 128. To the shaft 128 is secured a second arm 130 upon which is mounted a cam roll 132 engaging a peripheral cam face formed on the cam disc 72.

The mechanism for actuating the jack to feed the shoe past the operating tools comprises a feeding lever 132 and a bar 134 connecting the feeding lever with the forward end of the jack. During the operation on the shoe the lever 132 is swung toward the left as viewed in Fig. 1 to actuate the jack to feed the marginal portion of the shoe past the operating tool. The lever 132 pivoted at 136 on the frame is actuated by mechanism comprising a lever 138 pivotally connected with the feeding lever and pivotally supported by a hanger 140. The hanger in turn is pivotally supported by a lever 142 which will be hereinafter termed the fulcrum carrying lever. The lever 138 is swung about the pivotal connection between the hanger 140 and the fulcrum carrying lever to actuate the feeding lever during the operation

of the machine by mechanism comprising a lever 144 connected with the lever 138, a bell crank cam lever 146, and a link 148 connecting the cam lever with the lever 144. The 5 cam lever carries a cam roll 150 arranged to engage a cam on the cam disc 100.

To enable the mechanism for actuating the jack to feed the shoe to impart the proper feeding movement to the jack for shoes of 10 different sizes the mechanism is adjusted to accord with the size of the shoe placed in the machine. At the time when the shoe is placed in the machine the fulcrum carrying lever is unlocked and as the shoe is brought to 15 the correct position for starting the operation the said lever will be adjusted through the connections between said lever and the jack to a position depending upon the size of the shoe. The adjustment of the feeding 20 lever thus produced will effect the proper adjustment of the fulcrum of the lever 138.

The driving mechanism for the machine comprises a driving shaft 152 upon which is mounted a fast pulley 154 and a loose pulley 25 156. The driving shaft carries a bevel gear 158 which meshes with a bevel gear 160 mounted on the upper end of a vertical counter-shaft 162. Fixed upon the counter-shaft is a disc carrying the driving member 30 164 of a friction clutch the driven member of which, indicated at 166, is carried by a sleeve 168 loosely mounted on the counter-shaft. The sleeve 168 also carries a spiral gear 170 meshing with a spiral gear on a horizontal counter-shaft 176. During the 35 operation on the shoe the friction clutch is engaged and the counter-shaft 176 is driven at speed depending upon the speed of the driving shaft 152.

40 The pattern cam shaft 66 is driven through a spiral gear 178 journaled on a shaft 180 and meshing with a spiral gear 182 secured to the upper end of the pattern cam shaft. The spiral gear 178 is driven through a 45 clutch connection from a bevel gear 184.

During the operation on the shoe the bevel gear 184 is driven through a train of gears 186, 188, 190, 192, and 194 from a sleeve 196. The sleeve 196 is driven through suitable 50 variable speed transmitting mechanism from a counter-shaft 198 which in turn is driven from the shaft 176 through intermeshing gears 200 and 202. Mechanism for adjusting the variable speed transmitting mechanism intermediate the counter-shaft 198 and the sleeve 196 is controlled through a link 204 from the fulcrum carrying lever 142.

In starting the machine the sleeve 168 is elevated by the operator to engage the 55 members 164 and 166 of the main driving clutch and is held in elevated position by a latch. When a point in the operation of the machine on the shoe is reached at which the machine is to be stopped, this latch is released through suitable connections actuated

from the pattern cam shaft, the members of the main driving clutch are disengaged and the shaft 176 is stopped by suitable stopping devices.

The edge setting mechanism of the edge 70 setting machine illustrated in the drawings (see Figs. 9, 10 and 11) comprises a vibratory carrier 206 upon which are mounted the edge setting tools. The carrier 206 is secured to the forward end of a slide 75 208 mounted for forward and rearward movements in a guideway in a block 210 pivoted on the lower end of a vertical shaft 212 secured in a bracket 214 attached to a carriage 216. The block 210 is held in position on the shaft 212 by means of a bolt 218 upon the upper end of which is threaded a nut 220.

Oscillatory movements are imparted to the block 210 from a rotary shaft 222 journaled in bearings in the carriage 216 through a pitman 224 pivotally connected at one end with an arm 226 on the block 210 and carrying at its other end an eccentric strap 228 surrounding an eccentric 230 formed on the lower end of the shaft. The shaft 222 is driven through intermeshing spiral gears 232 and 234 from a horizontal shaft 236 which constitutes the main shaft of the edge setting head. The main shaft 236 is journaled 80 in bearings formed on the carriage 216 and is driven from an electric motor secured to said carriage.

Upon the forward end of the carrier 206 is mounted an edge setting tool 240 for operating on the sole edge about the forepart of the shoe and an edge setting tool 242 for operating on the sole edge along the shank. A longitudinally movable rod 244 is connected at its forward end by a universal joint with the carrier 206 and a coiled spring 246 surrounding the rod is interposed between an adjustable sleeve 248 threaded into the bracket 214 and a collar 250 secured to the rod. 100

The edge setting machine is provided with a work table or guide 252 similar to the work table of the edge trimming machine arranged to engage in the crease between the upper and a projecting margin of the sole of a shoe. This work table is secured to the machine frame and is arranged to extend in front of the tool which is in operating 105 position.

To enable the setting tools 240 and 242 to be moved alternatively into operating position the carriage 216 is eccentrically mounted in a bearing in a rotatably adjustable supporting ring 254 which in turn is mounted to rotate in a bearing or race way formed by arms 256 on the machine frame. The carriage 216 is pivotally connected with one end of a pitman 258 to the opposite end of which is secured an eccentric strap embracing an eccentric 260 secured to a rock shaft 110 115 120 125 130

262 journaled in the frame of the machine. The ring 254 is rotatably adjusted by the rotation of the rock shaft 262 through a connection consisting of an arm 264 secured to the rock shaft and a link 266 connecting the arm with the ring 254. The rock shaft 262 is rotated manually to adjust the carriage 216. The mechanism for rotating the shaft comprises a gear 267 mounted on the shaft 10 and a gear segment 268 secured to a second rock shaft 270 and meshing with the gear 267. An arm 272 is secured to the shaft 270 and is connected by a link 274 with a hand lever 276 pivoted on the machine frame.

15 When the edge setting machine is started along the shank of a shoe the ring 254 is adjusted in the position shown in Fig. 10 and the edge setting tool 242 is located in operating position as shown in this figure.

20 When the forepart of the shoe sole is reached, the hand lever 276 is swung by the operator until the parts assume the position shown in Fig. 9 in which position the edge setting tool 240 is in engagement with the sole edge.

25 When the shank of the shoe is reached in setting the edge of the sole on the side of the shoe last operated upon the hand lever 276 is swung back to its original position to bring the shank tool 242 again into operation.

30 The ring 254 is held in adjusted position by the friction exerted on the ring by the arms 256.

The base of the edge setting machine is similar to that of the edge trimming machine and it will be seen from a comparison of Figs. 4 and 5 with Figs. 9 and 10 that the shoe is presented to the operating tools in each machine so that the working face of the setting tool is at the same angle to the sole surface as the trimming tool at corresponding points in the edge setting and edge trimming operations. This permits the edge setting tool which is in operation to be vibrated in a fixed plane with its working

face at a constant angle to said plane and to act therefore to the best advantage in finishing the edge surface in a uniform and satisfactory manner.

The invention having been thus described what is claimed is:—

1. The method of making shoes which comprises presenting a lasted shoe successively to an edge trimming tool and to an edge setting tool, and imparting relative tipping positioning movements to the shoe 55 and tools as the point of operation is transferred about the shoe to present the working faces of the trimming and edge setting tools at the same angle to the sole surface at corresponding points in the operation of the 60 tools.

2. The method of making shoes which comprises presenting a lasted shoe successively to an edge trimming tool and to an edge setting tool, guiding the shoe during each 65 operation by engaging a guiding device with an outline on the shoe, and imparting relative tipping positioning movements to the shoe and tools as the point of operation is transferred about the shoe to present the 70 working faces of the trimming and edge setting tools at the same angle to the sole surface at corresponding points in the operation of the tools.

3. The method of making shoes which 75 comprises presenting a lasted shoe successively to an edge trimming tool and to an edge setting tool, guiding the shoe during each operation and imparting tipping positioning movements to the shoe as the point 80 of operation is transferred about the shoe to present the working faces of the trimming and edge setting tools at the same angle to the sole surface at corresponding points in the 85 operation of the tools.

In testimony whereof I have signed my name to this specification.

LAURENCE E. TOPHAM.
